UNITED STATES PATENT OFFICE

ALBERT A. GORDON AND ROLAND M. COOK, OF WORCESTER, MASSACHUSETTS, ASSIGNEES TO CROMPTON & KNOWLES LOOM WORKS, OF WORCESTER, MASSACHUSETTS, A CORPORATION OF MASSACHUSETTS

DOBBY LEVER FOR LOOMS

Application filed March 21, 1928. Serial No. 263,467.

This invention relates to improvements in dobbies for looms and it is the general object of the invention to provide a two-part dobbey back lever which shall have a bearing portion of a width substantially greater than twice the thickness of the sheet stock from which the lever parts are made.

Patent to Holmes No. 1,451,828 shows a dobbey back lever made of two sections of sheet steel both of which are substantially similar and are riveted together at points spaced from the ends of the lever so that said sections may be separated to permit ready insertion or removal of a dobbey hook.

15 The dobbey back lever has a central bearing which receives a stud carried by the dobbey jack or harness lever and as constructed heretofore this bearing has been substantially double the thickness of the

20 stock of which a single section is made. Many thousands of dobbey back levers made according to the aforesaid Holmes patent have gone into successful use but there are certain instances where it is desirable to

25 provide a bearing somewhat wider than that shown in the said Holmes patent and it is an important object of our present invention to provide the additional bearing by placing between the two sections of the 30 lever a thin metal strip which is held in position between said lever sections.

The lever as shown in the said application is made of two identical parts each with an offset at one end and when being 35 assembled a pair of the sections is placed as they come from the press, one member of the pair is then turned end for end about the axis of the bearing as a center, and is then turned over along the longitudinal axis

40 of the section. This brings the offsets on opposite sides of the center line, as they should be, and also correctly places those portions of the ends of the lever which engage fixed structure in the dobbey to position the harness levers. It is a further 45 object of our present invention to use these features of the Holmes lever and in addition provide each section with a depression so formed that when one of the pair of sections is reversed a space will be defined be-

tween the sections by the depressions into which the bearing strip may be placed.

It is a more detailed object of our present invention to provide a depression in each section of the lever which shall be symmetrical about an axis extending transversely of the lever through the bearing. In some instances we may also form the depression so that the same is symmetrical about a longitudinal axis extending through 55 a bearing, but it is not necessary that the depression be symmetrical with respect to the longitudinal axis.

With these and other objects which will appear as the description proceeds, our invention resides in the combination and arrangement of parts hereinafter described and set forth in the claims.

In the accompanying drawings, wherein we have shown a convenient embodiment 70 of our invention,

Fig. 1 is a vertical section through a dobbey equipped with our improved form of back lever,

Fig. 2 is a front elevation of an improved 75 lever according to our present invention,

Fig. 3 is an end view taken in the direction of arrow 3, Fig. 2,

Fig. 4 is a longitudinal section on line 4-4 of Fig. 2 but with the component parts 80 of the lever in spaced relationship such as they assume before assembly,

Fig. 5 is a detailed vertical section on line 5-5 of Fig. 1,

Fig. 6 is a fragmentary view of the central portion of a lever having a modified 85 form of depression,

Figs. 7, 8 and 9 are diagrammatic views of the method of assembling the lever starting with two exactly similar sections, and 90

Fig. 10 shows a further modification of the form of depression.

Referring to Fig. 1 the dobbey frame 10 is provided with fingers 11 and 12 which cooperate, respectively, with lower and upper hooks 13 and 14. Said hooks are connected in pairs to a dobbey back lever indicated at L, the upper hook being positioned by means of one of the levers 12 through an upright rod 15. Oppositely 100

reciprocating upper and lower knives 16 and 17, respectively, cooperate with the hooks and the vertical position of the latter is determined by a pattern mechanism 18 located under the fingers. A rod 19 affords pivotal support for a plurality of harness levers or dobby jacks 20 each of which is pivotally connected as at 21 to one of the levers L. During the operation of the loom 5 the pattern mechanism 18 will receive periodic angular movements to raise and lower the levers 11 and 12 in proper sequence to provide the weave desired. The dobby has upper and lower cross girts 21 and 22, respectively, which are held in fixed position and limit movement of the dobby lever to the left as viewed in Fig. 1. The harness frames and warps controlled thereby are operatively connected to the jacks 20. 10 The matter thus far described is of common construction and with the exception of the lever L forms no part of our present invention.

The back levers L are formed of two 25 similar lever sections 30 and 31. As shown more particularly in Fig. 4 each section has a straight end 32 and an offset end 33 and the sections are provided with aligning openings 34 to receive rivets 35. The parts are 30 assembled as shown in Fig. 3 so that there is an offset end 33 at each end of the lever L and it will be seen that these offsets lie on opposite sides of the central line of the lever L as viewed in Fig. 3. The purpose 35 of this construction is to afford proper connections with the fingers 11 and 12. By referring to Fig. 5 it will be seen that the lower hooks 13 have direct engagement with the levers 11 and that the upstanding rods 40 15 pass between the levers 11 and extend upwardly in a straight line to have lifting engagement with the upper hooks 14. The offset in the levers are therefore on opposite sides of the center line because of the 45 fact that the rods 15 must pass between the levers 11. As shown herein the portions of the two sections 30 and 31 between the ends thereof are substantially straight but they may be formed as shown in said 50 Holmes patent so that the ends may be placed under a tension to provide more satisfactory bearings for the dobby hooks. That much of the lever L which has already been described may be similar to the structure set 55 forth in the aforesaid Holmes patent.

As previously stated our invention is more particularly concerned with the manner of increasing the bearing for the stud 21 and in carrying our invention into effect we provide each of the sections 30 and 31 with a depression 50 through which the bearing openings 51 extend. As shown in Fig. 2 the depression is diamond shape so that said depressions are symmetrical about 60 perpendicular axes which are also perpen-

dicular to the axis of the openings of bearing 51. As shown in Fig. 6, however, the depression 60 is not necessarily symmetrical around an axis extending longitudinally of the lever but it is symmetrical around an axis transverse of the lever and extending through the center of the bearings 51. A strip of sheet metal indicated at 61 may be formed of substantially the same shape as the depression and may be of such thickness as is desired to give the necessary increase in width of the bearing. Said strip is provided with a punched bearing 62 which aligns with the bearings 51.

There is but one type of dobby section and in assembling the lever two of these sections which are exactly alike will be placed substantially as shown diagrammatically in Fig. 7. The upper section will then be given a one-half turn around its longitudinal axis so that the offset portion 33 will be oppositely disposed with respect to the corresponding part of the lower section to assume the position shown in Fig. 8. Said upper section is then given a half revolution around the axis of the bearings 51 or around the center line C so that the parts assume the positions shown in Fig. 9. The strip 61 is then placed in the recess of the lower member, the top member superposed upon the lower member and the two sections riveted, after which a reamer may be passed through the openings 51 and 62 so that the bearing is made smooth and free from burrs. If the strip 61 has been properly formed it will be held very tightly in the depressions by the rivets 35 and the fact that it is of non-circular form will prevent the same from turning to become improperly positioned with respect to the dobby lever. The strip 61 preferably fills the cavity formed between the sections by the oppositely extending depressions.

As shown in Fig. 10 we may make the depressions elliptical, as at 70, with the long axis extending longitudinally of the lever and the short axis transversely thereof. A bearing strip 71 is formed to fit into and substantially fill the depressions 70.

It is preferable to have the depressions non-circular and they must be symmetrical about a transverse axis which passes through the center of the bearing B due to the fact that one of the sections is rotated about the axis of the bearing one-half a turn in the assembly of the lever. The fact that one of the sections is turned over along its longitudinal axis accounts for the fact that it is not necessary that the depression shall be symmetrical with respect to the longitudinal axis.

From the foregoing it will be seen that we have provided a very simple composite dobby back lever having an increased bearing surface which is afforded by striking a

depression into each section or member of the lever in such a way that the depression is symmetrical with respect to a transverse axis. Furthermore, a single type of section may be used because of the fact that in the assembly of the lever one section or member is turned end for end and then inverted relatively to the other member, or in other words, one member is given a half turn about two mutually perpendicular axes one of which is the axis of the bearing of the finished lever. It will further be seen that the depression may be symmetrical about a longitudinal axis although this feature is not essential and it will also be noted that the depressions and the plate or strip 61 located therein are non-circular and that the plate is so formed as to be held tightly in position when the two sections or members are riveted together. The horizontal dimension of the depression is preferably sufficient to require contact between the broadened portions of the levers for the extreme positions of the dobby back levers when one of them is in the position shown in Fig. 1 and the adjacent lever is moved by having one or the other of the hooks connected thereto moved to the right.

Having thus described our invention it will be apparent that changes and modifications may be made therein by those skilled in the art without departing from the spirit and scope of the invention and we do not wish to be limited to the details herein disclosed, but what we claim is:

1. A dobby back lever formed of two substantially similar sections each with a body portion, each section formed with a non-circular depression to provide a bearing portion out of the plane of the body portion, said depressions facing each other and being symmetrical about a transverse axis, a non-circular bearing element substantially filling the cavity formed by the depressions, and means passing through the sections at points removed from the non-circular depressions and being the sole means for holding said sections together.

2. A dobby back lever formed of two substantially similar sections each with a body portion, each section formed with a non-circular depression to provide a bearing portion out of the plane of the body portion, said depressions facing each other and being symmetrical about a transverse axis, a non-circular bearing element substantially filling the cavity formed by the depressions, and means to hold the sections together to prevent relative angular movement thereof in a direction parallel to the planes of their body portions, said means passing through parts of the body portions other than those in which the depressions are formed.

3. A dobby back lever formed of two substantially similar sections each with a body

portion, each section formed with a non-circular depression to provide a bearing portion out of the plane of the body portion, said depressions facing each other and being symmetrical about a transverse axis, a non-circular bearing element substantially filling the cavity formed by the depressions, said depressions forming a widened bearing portion for the lever, and means extending through the body portions at spaces removed from the widened bearing portion to hold said sections together thereby leaving the sides of the widened portion smooth.

In testimony whereof they have hereunto affixed their signatures.

ALBERT A. GORDON.
ROLAND M. COOK.
